DOOR MECHANISM FOR EXCAVATING APPARATUS

Joseph P. Murtaugh, Oak Park, Ill., assignor to
American Brake Shoe Company, a corporation
of Delaware

Application July 8, 1942, Serial No. 450,127

14 Claims. (Cl. 214—146)

The present invention relates to excavating apparatus and more in particular to novel door mechanism for dippers, buckets, scrapers or the like.

Among the objects of the present invention is to provide a readily detachable hinge connection for the door of an excavating implement whereby the said door will have proper seating relation with other members of the implement in closed position under all conditions and irrespective of irregularities and variations in the castings or other members forming the said excavating implement.

Still another object of the present invention is to provide a novel means for hingedly connecting the door of excavating apparatus to provide for the application of said door thereto without expensive machining and finishing, the said hinge connection permitting adjustment of the door with respect to the hinge element or elements so as to provide a suitable closure at all times.

More particularly the present invention comprehends a flexible, pivotal connection for a door for excavating apparatus with the provision of means limiting such pivotal movement, and which means may take the form of cushioning elements for effecting proper seating relation of the door and for limiting its pivotal movement with respect to the hinge elements.

Another object within the purview of the present invention is to provide novel means in the form of abutting elements on the door and one or more operating elements for the excavating apparatus, which abutment means may comprise cushioning elements limiting the door in its movement to open position.

Other objects, features, capabilities and advantages are comprehended by the invention, as will later appear and as are inherently possessed thereby.

Referring to the drawings:

Figure 1 is a view in side elevation of an excavating implement incorporating novel structure in accordance with the present invention;

Figure 2 is a view in elevation of the door for the said implement shown in Figure 1 of the drawings;

Figure 3 is a view in perspective of a link shown in Figure 1, and incorporating novel construction for limiting movement of the door for said implement; and

Figure 4 is a fragmentary view in section taken in the plane represented by line 4—4 of Figure 2 of the drawings.

Referring now more in detail to the drawings,

an excavating implement incorporating structure in accordance with the present invention is shown as comprising a dipper formed with a back 2, a front 4, and interconnecting sides 6 and 8, which may be of conventional design but as shown herein conform to the disclosure of a copending application for Excavating implements, Serial No. 468,078, filed December 7, 1942.

As is conventional in this type of structure, the front at its upper or cutting edge 10, is provided with a plurality of teeth 12, and the said back is provided with the lugs, as at 14, adjacent the sides 6 and 8 for connection to a lifting bail 16. Also connected to the back 2, as at 18, is a dipper stick 20 which is further connected to the back 2 through the medium of the links 22, pivotally connected as at 24, to the pair of lugs 26 and 28 disposed in spaced relation to one another and formed on the said back 2.

The dipper herein disclosed is further provided with a door or closure member 30 adapted to close the opening formed by the front, back and side elements hereinbefore referred to, and which door is pivotally connected, as at 36, to the hinge lugs 38 formed on the back member 2, through the medium of hinges 32 and 34 of the offset arm type. The door 30 is further provided with latch mechanism, generally referred to as 40, which holds the door in locked position and which may be operated to release said door and permit discharge of material carried by the dipper.

The present invention in one of its aspects is concerned primarily with a suitable flexible mounting for the door 30 on the arms 32 and 34 to permit seating of the door under all conditions and irrespective of irregularities and variations in the formation and finishing of the front, back and side elements defining the opening for the dipper. Such novel connection is provided in the present illustration by means of pintles 42 and 44 mounted in lugs or brackets such as 46 provided on the face of the door 30, and which serve as hinge means mounted in the arms 32 and 34 in spaced relation to the free ends thereof. This hinge connection permits relative movement of the door 30 in respect to the hinge elements 32 and 34 and provides for the seating thereof under all conditions.

In order to limit the relative movement of the door with respect to the arms, each of said arms is provided on opposite sides of the hinge connection thereof to the door with the abutment pads 48 and 50 which are disposed to engage with the door to limit its relative movement with

respect to said arms. While these pads may take any form desired, nevertheless the present illustration discloses the same as being constituted of some resilient compressible material such as rubber or the like, which are secured to the inner face of the arms as by means of a screw or the like, and which are adapted to seat in recesses or sockets 52 provided in opposed relation thereto on the face of the door 30, thus assuring proper seating of the door and to cushion its movement with respect to the hinge elements.

As a further novel feature of construction, the door 30 is provided with an abutment flange 54 extending laterally of the same and which is in position to engage the abutment pads 56 carried by the links 22 at the time that the door 30 reaches its full open position. These pads 56 are preferably mounted in sockets or recesses 58 provided in the links 22 and secured therein by the bolts, screws or the like 60. While the said pads may be of any desired material, the same are preferably of some resilient or compressible material such as rubber or the like, so as to cushion and control the pivotally mounted door as the same is swung into full open position, thus providing a novel arrangement to prevent injury or damage to the parts of the excavating dipper and its operating elements.

While I have herein described and upon the drawings shown an illustrative embodiment of the invention, it is to be understood that the invention is not limited thereto but may comprehend other constructions, arrangements of parts, details and features without departing from the spirit of the invention.

What is claimed is:

1. In an excavating implement the combination of a front member, a back member and interconnecting side members forming a bottom opening, a closure for said opening, one or more hinge elements for said closure, means for hingedly connecting said one or more hinge elements adjacent one end thereof to one of said members, means for hingedly connecting said one or more hinge elements intermediate the ends thereof to said closure, and cushioning means between said one or more hinge elements and said closure and on opposite sides of said hinge connection between said closure and said one or more hinge elements for limiting the relative movement of said closure with respect to said one or more hinge elements.

2. In an excavating implement the combination of a front member, a back member and interconnecting side members forming a bottom opening, a closure for said opening, one or more hinge elements for said closure, means for hingedly connecting said one or more hinge elements adjacent one end thereof to one of said members, means for hingedly connecting said one or more hinge elements intermediate the ends thereof to said closure, and pads disposed on opposite sides of said hinge connection for said closure and arranged between said one or more hinge elements and said closure for limiting the relative movement of said closure with respect to said one or more hinge elements.

3. In an excavating implement the combination of a front member, a back member and interconnecting side members forming a bottom opening, a closure for said opening, one or more hinge elements for said closure, means for hingedly connecting said one or more hinge elements adjacent one end thereof to one of said members, means for hingedly connecting said

one or more hinge elements intermediate the ends thereof to said closure, and cushioning pads carried by said one or more hinge elements on opposite sides of said hinge connection for said closure and adapted to cooperate therewith to limit relative movement thereof with respect to said one or more hinge elements.

4. In an excavating implement, the combination of a closure member, one or more hinge members for connecting the same to said implement, a hinge connection between said closure member and said one or more hinge members intermediate the ends of the latter, and means carried by one of said first or second named members on opposite sides of said connection for limiting relative movement therebetween.

5. In an excavating implement, the combination of a closure member, one or more hinge members for connecting the same to said implement, a hinge connection between said closure member and said one or more hinge members intermediate the ends of the latter, and cushioning means carried by one of said first or second named members on opposite sides of said connection for limiting relative movement therebetween.

6. In an excavating implement, the combination of a closure member hinged to said implement, operating means for said implement, one or more link members connecting said means to said implement, and means on said closure and said one or more link members adapted to cooperate for limiting movement of said closure member.

7. In an excavating implement, the combination of a closure member hinged to said implement, operating means for said implement, one or more link members connecting said means to said implement, and cushioning means on said closure and said one or more link members adapted to cooperate for limiting movement of said closure member.

8. In an excavating implement, the combination of a closure member hinged to said implement, operating means for said implement, one or more link members connecting said means to said implement, said closure member being provided with a flange, and means carried by said one or more link members adapted to engage with said flange for limiting movement of said closure member.

9. In an excavating implement, the combination of a closure member hinged to said implement, a dipper stick connected to said implement, one or more link members connecting said implement and said dipper stick, said closure member being provided with a flange, each of said one or more link members having a recess, and a cushioning member carried in said recess to cooperate with said flange for limiting movement of said closure member.

10. In an excavating implement, the combination of a closure member, one or more hinge members for connecting the same to said implement, a hinge connection between said closure member and said one or more hinge members intermediate the ends of the latter, abutment means between said closure member and said one or more hinge members, a dipper stick connected to said implement, one or more link members connecting said implement and said dipper stick, said closure member having a flange, and abutment means carried by said one or more link members engageable with the flange of said

hingedly connected door for limiting its movement in open position.

11. In an excavating implement, the combination of a closure member, one or more hinge members for connecting the same to said implement, a dipper stick connected to said implement, one or more link members connecting said implement and said dipper stick, and abutment means carried by said one or more link members engageable with said hingedly connected door for limiting its movement in open position.

12. In an excavating implement, the combination of a closure member, one or more hinge members for connecting the same to said implement, a dipper stick connected to said implement, one or more link members connecting said implement and said dipper stick, said closure member having an abutment, and abutment means carried by said one or more link members engageable with the abutment of said hingedly connected door for limiting its movement in open position.

13. In an excavating implement, the combination of a closure member, one or more hinge members for connecting the same to said implement, a hinge connection between said closure member and said one or more hinge members intermediate the ends of the latter, abutment

means between said closure member and said one or more hinge members, a dipper stick connected to said implement, one or more link members connecting said implement and said dipper stick, said closure member having laterally extending abutment means, and abutment means carried by said one or more link members engageable with said laterally extending abutment means of said hingedly connected door for limiting its movement in open position.

14. In an excavating implement, the combination of a closure member, one or more hinge members for connecting the same to said implement, a hinge connection between said closure member and said one or more hinge members intermediate the ends of the latter, abutment means between said closure member and said one or more hinge members, a dipper stick connected to said implement, one or more link members connecting said implement and said dipper stick, said closure member having abutment means, and abutment means carried by said one or more link members engageable with said laterally extending abutment means of said hingedly connected door for limiting its movement in open position.

JOSEPH P. MURTAUGH.
